Irving C. Matthes

UNITED STATES PATENT OFFICE

JOHN WALLERSTEIN, OF NEW YORK, N. Y.

IRONING TABLE

Application filed December 31, 1928. Serial No. 329,331.

This invention relates to ironing tables or boards and in particular to one upon which the opposite sides of a shirt or similar garment may be ironed without the necessity of removing the same from the board.

A particular object of my invention is to provide a compact, efficiently operated ironing board or table which will greatly increase the output of the ironer, particularly in commercial establishments and which will be constructed of few parts and which can be easily manipulated.

A still further object of my invention is to provide an ironing table having for use in combination therewith, movable sleeve boards which may be dropped out of the way when not in use to permit use of the table without interference. In ironing tables employed heretofore, it has been necessary for the ironer to completely remove the shirt or garment to be ironed after the bosom has been ironed and to reverse the shirt in order that the back of the garment may be ironed. In my improved table, the ironing board is pivoted and can be quickly revolved when one side of the garment has been ironed.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in side elevation of an ironing table constructed in accordance with my invention, the table end support being illustrated in outline position to illustrate its location when the ironing table was to be reversed.

Figure 2 is a top plan view of the ironing table illustrated in Figure 1.

Figure 3 is a section taken on the line 3—3 of Figure 1, a part thereof being broken away, and

Figure 4 is an enlarged fragmentary section taken at the center of a board and illustrating the construction of the board and the method of attaching the shaft thereto.

Referring to the drawings in detail, 5 indicates a heavy metal standard formed to provide a central web 6 and side flanges 7, the upper part of the standard terminating in a flat top 8 and the lower part of the standard being cast to provide an elongated base 9. The top plate 8 is arranged to support at its center the spaced journal brackets 10 in which are journalled the shaft 11. This shaft passes into the wooden portion 12 of the ironing table and is secured therein through the medium of suitable rivets or screws 13, the opposite ends of which maintain in place upon the board 12, the covering metal plate 14. The board itself is covered with a suitable pad 15 and is wrapped on both sides and edges in a cover 16 so that a smooth, level surface is provided for the ironing operation. The shaft is freely rotatable in the bearings 10 so that it can be revolved to iron the front and back of a shirt or similar garment which has been pulled thereover and preferably buttoned. The top 8 of the bracket has secured thereto the post 17 which supports in spaced relation with said top 8, an iron supporting shelf 18 upon which an iron 19 may be placed while the ironer is revolving the board or otherwise placing the garment to be ironed thereover.

In order that the revolving movement of the ironing table or board noted generally by the numeral 20 may be locked in any one of its revolved positions, I have cast upon the flange 7 of the standard 5, a plurality of bearings 21 in which are journalled, the cross shaft 22 which carries at its outer end the table holding arms 23, these arms being joined by the suitable tie rods 24. One of the arms 23 is extended at its upper end as at 25 and shaped to provide a handle through the medium of which the table locking device may be manipulated. Both of the arms 23 are shaped to provide locking cams 26 which extend forwardly and are arranged to engage the inner end of the ironing table 20 so that it is held securely in either of its revolved positions.

When a shirt is to be ironed, it is of course, drawn over the ironing board 20 and is buttoned, in the event that it is an open front

shirt after which the front of the shirt is ironed and upon completion of the ironing operation, the iron may be placed upon the shelf 18 and the handle 25 manipulated. A 5 rearward movement of the same will cause a throw of the arms 23 which will of course remove the cam 26 from beneath the edge of the ironing table 20 and will permit free rotation thereof until the back of the shirt is 10 uppermost at which time, it can be conveniently ironed.

In order that more stability may be given to the ironing table, I have hinged at the front edge of the base 9, a board end support 27, the hinge being indicated by the numeral 28 and the lower end of the support 27 being extended beyond the hinge so that it will contact with the floor as shown in outline in Figure 1, when it is thrown back to said 15 outline position. This support 27 is provided with an extension 29 which is arranged to underlie the end of the board 20 and firmly support the same during the ironing operation, it being of course understood that it 20 must be thrown back to the position shown in outline in order that the board may be revolved or that the article to be pressed may be placed over the ironing board.

In combination with my ironing board, I 30 may employ also suitable sleeve boards 30 which are arranged at one end of the ironing table 20 and are pivoted at one of their ends in a suitable frame 31. These sleeve board frames, there being one provided for each 35 of the sleeve boards, is preferably made from a piece of pipe flattened in its mid portion as at 32 where it is attached to the base through the medium of the suitable screws or rivets 33, the intermediate portion thereof 40 being bent as at 34 to provide a foot for engagement with the ground, the frame being a single piece and having its upper extremities joined through the medium of the rod 35 which acts as a holder for the brake 36 which 45 is pivoted beneath the sleeve board 30 at the center thereof and is arranged to ride loosely over the bars 35 and to hook thereover through the medium of its serrations 37 in order that the board 30 may be supported in 50 the same plane as the main ironing board 20. A suitable connecting rod 38 is employed through the end of each sleeve board 30 upon which it pivots, this rod being held between the end of the frame 31. When these sleeve 55 boards are not to be used, the braces 36 may be released and the boards of course will drop down to a vertical position which will also be assumed by the braces 36 and consequently no room will be taken up thereby.

60 The use of the sleeve boards 30, of course, facilitates the ironing inasmuch as the sleeves of the garment may be stretched out on the board, and ironed simultaneously with the front and back of the shirt or garment.

65 When the ironing table 20 is to be revolved,

the sleeve boards 30 will be dropped and the board support 27 will be moved to the position shown in outline in Figure 1. The board 20 will then be revolved and the support 27 moved into the position shown in Figure 1 to support the board, after which the sleeves, of course, may be brought up to position and the entire side of the garment ironed, including the sleeves.

It is evident therefore that in a construction of this character, I have provided a very solidly constructed ironing table in which the board portion may be revolved so that ironing of both sides of the shirt may be completed without the necessity of removing the shirt or other garment from the ironing board.

It is further evident that through the use of my improved ironing table, the sleeves may be ironed at the same time that the shirt is being pressed so cutting down the time necessary for the ironing operation.

It is also evident that through my improved construction I have provided a compact ironing board which is revolvable, which will occupy a small space and which may be manipulated very rapidly in order to carry out successfully the ironing operation.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. An ironing table comprising a standard, bearings thereon, a shaft revolvable in said bearings, a board secured to said shaft, a board holder pivoted to said standard and cam portions on said holder for engaging one end of the board to prevent free rotation thereof.

2. An ironing table comprising a standard, bearings thereon, a shaft revolvable in said bearings, a board secured to said shaft, a board holder pivoted to said standard, cam portions on said holder for engaging one end of the board to prevent rotation thereof, a support for the other end of said board, and a hinge connection between said standard and said support whereby the latter may be moved to permit rotation of the board.

In testimony whereof I affix my signature.

JOHN WALLERSTEIN. [L. S.]
